LINING FOR TUNNELS, SHAFTS, AND LIKE

Filed Nov. 7, 1927.

FIG. I

FIG. 3

9' FIG. 4

Inventor

James Harvey Humphries

by John Willms

UNITED STATES PATENT OFFICE

JAMES HARVEY HUMPHREYES, OF BICKLEY, KENT, ENGLAND

LINING FOR TUNNELS, SHAFTS, AND THE LIKE

Application filed November 7, 1927. Serial No. 231,431.

This invention relates to improvements in linings for tunnels, shafts and the like.

Such linings are commonly built up of rectangular curved or arcuate plates flanged on all four sides so that they can be bolted together when assembled against the wall of the tunnel or shaft. The plates hitherto have been produced with integral flanges by the use of press tools, or have been formed from flat plates by shearing them at the corners and bending by the edges to form the flanges.

The chief difficulty in manufacturing such plates is to avoid buckling or puckering of the flanges when the plate is bent to form an arc, and for this reason it has been necessary to keep the flanges narrow.

The object of my invention is to provide an improved plate or section for a tunnel or shaft lining in which flanges of considerable depth can be employed so that the rigidity of the plate and its resistance to bending stresses are greatly increased.

According to my invention a plate or section for a tunnel or shaft lining comprises a member of hollow box form having flanges of substantial depth with straight edges, two of the opposite flanges being inclined to the base at less than a right angle so that when a number of plates are assembled to form a ring the meeting flanges of adjacent sections will be parallel to each other.

The inherent rigidity of the plate due to the use of straight deep flanges renders the use of ribs or corrugations in the base unnecessary, but if desired the base may be dished or domed to strengthen the plate still further.

My invention is illustrated in the accompanying drawings in which:—

Figure 1 is a diagrammatic view shewing the method of assembling a number of plates to form a curved line.

Figure 2 is an end elevation of a single plate.

Figure 3 is a section through the junction of two plates.

Figure 4 is a section at right angles to the section of Figure 3.

50 In the form illustrated each plate is of

rectangular outline and has a dished base *a*, side flanges *b* and end flanges *c*. The flanges are of substantial depth and their free edges are straight so that when the plates are assembled as shewn in Figure 1 55 the edges of the side flanges form chords of a circle concentric with the wall of the tunnel or shaft.

Each plate is formed from a flat rectangular steel or other sheet which is notched near the corner of each end edge for a depth equal to the depth of the flanges. The side flanges are cranked up at right angles to the base and their extremities *d* turned in as shewn in Figures 2 and 3. The end flanges are cranked 65 up so that they make an angle with the base which is less than a right angle but which will depend on the radius of the tunnel or shaft for which the plates are intended. The tongues or extremities *d* of the side flanges 70 which lie against the inner faces of the end flanges are secured to the end flanges by rivets, *e*. Preferably the exposed ends and corners of the end flanges are then welded to the side flanges as shewn at *f* in Figures 2 and 3 to 75 strengthen the joint and prevent the entry of moisture which would set up corrosion.

The dishing of the plates which is shewn in Figures 1 and 2 may be effected either before or after the cranking up of the flanges. 80

In assembling the plates to form a lining suitable packing material *g* is placed between the faces of the meeting flanges of adjacent plates and the end flanges are secured together by bolts *h* some of which preferably pass through the tongues on the side flanges as well as through the end flanges as shewn in Figure 3.

The joints between the end flanges of plates in adjacent rings are staggered as indicated 90 in Figure 3 and the adjacent side flanges are secured together by bolts *j*.

I claim:—

1. A unit for the construction of tunnel and shaft linings comprising a rectangular plate 95 having pairs of integral marginal flanges connected thereto along straight lines, the edges of said flanges being substantially parallel with said lines of connection and means securing portions of adjacent flanges together at 100

the corners of the unit, the flanges of one pair of flanges being disposed in a plane less than a right angle with respect to said plate.

2. A unit for the construction of tunnel and shaft linings comprising a rectangular plate having a pair of integral side flanges and a pair of integral end flanges joined to the plate along straight lines, the side flanges being disposed at substantially a right angle to said plate and the end flanges being disposed at less than a right angle to said plate, and means securing adjacent portions of the said flanges together at the corners of said units.

3. A unit for the construction of tunnel and shaft linings comprising a rectangular plate having a pair of integral side flanges and a pair of integral end flanges joined to the plate along straight lines, the side flanges being disposed at substantially a right angle to said plate and the end flanges being disposed at less than a right angle to said plate, one pair of said flanges having inturned ends engaged with and secured to end portions of the flanges of said other pair of flanges.

4. A unit for the construction of tunnel and shaft linings comprising a dished, rectangular plate having pairs of integral marginal side flanges and end flanges connected thereto along straight lines, one pair of said flanges being disposed at a right angle to the plane of said plate and the other pair of said flanges being disposed at less than a right angle to said plate and means connecting said flanges together at the corners of the units.

5. A unit for the construction of tunnel and shaft linings comprising a dished, rectangular plate having pairs of integral marginal side flanges and end flanges connected thereto along straight lines, one pair of said flanges being disposed at a right angle to the plane of said plate and the other pair of said flanges being disposed at less than a right angle to said plate, and the free edges of said flanges being parallel with said lines and means connecting said flanges together at the corners of the units.

In testimony whereof I affix my signature.
JAMES HARVEY HUMPHRYES.
